No. 36,454.

Patented July 21, 1903.

UNITED STATES PATENT OFFICE.

SETH H. LEAVENWORTH, OF CINCINNATI, OHIO.

DESIGN FOR A MOUNTING FOR DISHES OR SIMILAR ARTICLES.

SPECIFICATION forming part of Design No. 36,454, dated July 21, 1903.

Application filed April 20, 1903. Serial No. 153,580. Term of patent 7 years.

To all whom it may concern:

Be it known that I, SETH H. LEAVENWORTH, a citizen of the United States, residing at Cincinnati, in the county of Hamilton and State of Ohio, have invented a new, original, and ornamental Design for a Mounting for Dishes or Similar Articles, of which the following is a specification.

The features of the said design are set forth in the accompanying drawing, making a part of this specification, in which the figure is a perspective view showing the design mounting.

Having described my invention, what I claim as new, and desire to secure by Letters Patent, is—

The ornamental design for a mounting for dishes and similar articles as herein shown.

In testimony whereof I have hereunto set my hand.

SETH H. LEAVENWORTH.
